UNITED STATES PATENT OFFICE.

FRED S. NELSON, OF CHICAGO, ILLINOIS.

CARD HOLDER.

Application filed June 9, 1924. Serial No. 718,822.

To all whom it may concern:

Be it known that I, FRED S. NELSON, a citizen of the United States, residing at Chicago, in the county of Cook and State of Illinois, have invented certain new and useful Improvements in Card Holders, of which the following is a specification.

This invention relates to a novel and improved card holder and has for its primary object to provide a holder for cards which is readily reversible so that the holder may be placed in a plurality of positions.

A further object is to provide a card holder which may be detachably supported by a hinge.

A still further object is to provide a reversible card holder supported by a hinge and readily detachable therefrom, whereby it may be readily reversed.

Another object is to provide a card holder preferably rectangular in form, which may be readily supported with either side vertical.

A further object is to provide a card holder making easy the insertion and withdrawal of cards therefrom.

A further object is to provide a card holder which may be made of substantially one piece of material and which may be manufactured by simple stamping processes.

A still further object is to provide means for supporting a card holder in a rigid manner but so that the holder may be easily removed from its support.

Further objects will be in part apparent and in part pointed out during the progress of the description.

In the drawings forming a part of this specification in which I have illustrated a preferred embodiment of my invention,

Fig. 1 is an elevation of my improved card holder.

Fig. 2 is a section on the line 2—2 of Fig. 1.

Fig. 3 is a section on the line 3—3 of Fig. 1.

Fig. 4 is a detail of the construction shown in the upper right hand corner of Fig. 1.

Fig. 5 is a view similar to Fig. 1 showing my card holder in another position with respect to its hinge.

Referring now to the drawings, my card holder is designated generally by the numeral 1 and may comprise a metal plate 2 of rectangular form and having three of its four edges bent over to form the holding

means 3 for a card or the like. The fourth edge is not provided with this folded over portion but is provided with a channel shaped piece 4 hinged to the plate 2 as at 5, 60 and embracing the edge.

My card holder is designed particularly for use in the display of advertising matter and is very useful in shop windows although by no means limited to that use. Card holders known to me have generally been open to various objections, one of which is that they are difficult to remove when washing windows, re-arranging window displays, or the like, and to avoid this objection and 65 others I provide a supporting means exemplified by a hinge comprising two leaves 6 and 7. The leaf 6 is adapted to be attached to a wall or a window frame and the leaf 7 is made preferably wedge-shaped and 70 provided with an opening near its end which is adapted to be pivotally fastened to the plate 2 as by a bolt or screw 8.

Concentrically arranged in respect to the fastening means 8 are a plurality of supports 9 which may be conveniently formed by stamping out a portion of the plate 2. These supports project from the rear of the plate 2, as plainly shown in Fig. 2, and are 75 so arranged as to receive the leaf 7 of the hinge and to support the inclined edge of said leaf at the bottom of said support, as 80 plainly shown in Figs. 1, 2 and 5.

In use the leaf 6 of the hinge is fastened to any suitable support and the holder is 85 then connected to the leaf 7 by the means 8. If it is desired to support the holder in the horizontal position shown in Fig. 1, it is merely necessary to slide the support 9 over the lower edge of the hinge-leaf 7. The 90 weight of the holder will then tend to rotate the holder about the means 8, thereby forcing the support 9 into firm engagement with the leaf 7 and providing an extremely rigid support.

If it is desired to reverse the holder so as to have the card contained therein face rearwardly, it is only necessary to remove the holder, turn it about its horizontal axis through 180°, replace the fastening means 8 95 and engage the bottom edge of the leaf 7 with the support 9.

If it is desired to change the holder so as to have the edge which is horizontal in Fig. 1 vertical, it is only necessary to remove the support 9 from the hinge-leaf 7 100 and swing about the fastening means 8 105

and engaging the leaf 7 with the support 9" or 9'", as the case may be. This arrangement is illustrated in Fig. 5, and I prefer to use a pivoted catch 11 to provide increased 5 stability for this position of the holder.

In any of these positions the holder may be readily swung about the pintle 10 of the hinge and thus moved out of the way for window washing or other purposes, after 10 which it may be replaced in its original position.

In the above description of the use of my holder reference is made to the removal and replacing of the fastening means 8, which 15 may be done if desired by the use of a bolt for said fastening means. However, I prefer to use a rivet for the fastening means 8 which will permit pivotal movement of the plate 2 thereabout and I provide for the 20 reversal of the card holder by making the pintle 10 of the hinge easily removable whereby, when it is desired to reverse the holder, it is merely necessary to draw out 25 said pintle, turn the holder about its horizontal axis through 180° and re-assemble the hinge, of course engaging the leaf 7 with the support 9'. When it is desired to employ the supports 9" or 9'" it may or 30 may not be necessary to remove the pintle depending upon the proximity to the support.

In any position of the card holder cards may be readily placed therein and removed 35 therefrom by swinging the channel member 4 about its hinge 5. If desired, means may be employed to fasten the channel member in place but normally I find this unnecessary. I prefer to provide this hinged channel piece at the end of the holder remote 40 from the support whereby cards may be readily inserted and removed.

The wedge shape of the leaf 7 provides an extremely substantial support. Not only does the weight of the holder force the 45 edge of the leaf into engagement with the bottom of the support, but by arranging the various supports as shown, I increase the distance from the means 8 to the support, thereby obtaining a longer lever arm 50 for the support and a bracing action.

From the above it will be seen that I have provided a novel and improved card 55 holder which is extremely simple to manufacture, which may be readily applied, and which may be placed in any one of a plurality of positions with a minimum of labor and which, furthermore, may be easily swung out of the way.

I am aware that changes in the form, con-

struction and arrangement of parts may be 60 made without departing from the spirit and without sacrificing the advantages of the invention and I reserve the right to make all such changes as fairly fall within the scope 65 of the following claims.

I claim:—

1. A card holder having a plurality of supports thereon, each support adapted to engage a hinge, whereby said holder may 70 be supported in a plurality of positions relative to said hinge.

2. In combination, a card holder, a hinge having one leaf pivotally connected to said card holder, said card holder being provided with a support adapted to contact 75 with an edge of said hinge-leaf.

3. In combination, a hinge, a card holder pivotally connected to a leaf of said hinge, said card holder being provided with a plurality of supports on one side thereof, each 80 of said supports adapted to engage an edge of said hinge-leaf whereby said holder may be supported in a plurality of positions.

4. In combination, a hinge comprising two leaves and a removable pintle, and a card holder pivotally connected to one of said leaves, said card holder being provided with one or more supports, for the 85 purpose set forth.

5. In combination, a hinge having two 90 leaves and a removable pintle, a card holder pivotally connected to one of said leaves and provided with a plurality of supports, each adapted to engage an edge of said hinge-leaf, whereby a card holder may be supported in a plurality of positions.

6. In combination, a hinge comprising two leaves and a removable pintle, one of said leaves having inclined edges, a card holder pivoted near its end to said leaf and having one or more supports adapted to engage with said leaf, for the purpose set 100 forth.

7. A card holder provided with a plurality of supports adapted to engage an edge of a hinge-leaf and further provided with means for pivotally connecting said holder to said hinge-leaf, and a pivoted catch associated with one or more supports.

8. In combination, a supporting means, a card holder pivoted thereto and having a plurality of supports thereon said supports being disposed concentrically with said pivot and each support adapted to engage said supporting means to support said holder in any one of a plurality of positions with respect to said supporting means.

FRED S. NELSON.
